UNITED STATES PATENT OFFICE.

ESKEL NORDELL, OF CHICAGO, ILLINOIS.

COATING APPLIANCE.

Application filed September 12, 1919. Serial No. 323,443.

To all whom it may concern:

Be it known that I, ESKEL NORDELL, a citizen of the United States, residing at Chicago, in the county of Cook and State of Illinois, have invented certain new and useful Improvements in Coating Appliances, of which the following is a specification.

My invention pertains to improvements in appliances for coating the top and bottom closures or caps of fibrous or permeable receptacles with a grease-proofing composition, although the mechanism is susceptible of use in various other advantageous employments.

15 The leading object of the invention is to provide a mechanism simple in character and economical to manufacture, which will effectively and rapidly perform a smooth, uniform coating operation and properly remove the surplus coating material, the structure being such as to be readily and easily operated and unlikely to become deranged or damaged in service.

To enable those skilled in this art to understand the construction of a desirable embodiment of this invention, as well as its various functional advantages, in the accompanying drawings I have illustrated such an embodiment of the invention and throughout the various views of such drawings like reference characters refer to the same parts.

In these drawings:

Figure 1 is an end elevation of the appliance, certain of the parts being shown in vertical section for clearness of illustration;

Figure 2 is a plan view of the machine with parts broken away for a like purpose;

Figure 3 is an enlarged vertical section through one of the liquid-discharging nozzles on line 3—3 of Figure 2;

Figure 4 is a fragmentary front elevation of a portion of the mechanism, a part of the tray or trough being omitted to show one of the nozzles;

Figure 5 is a vertical section on line 5—5 of Figure 4 on an enlarged scale; and

Figure 6 is a vertical section through the straining mechanism.

50 Referring to the parts of the machine in detail, it will be noted that the mechanism comprises a main-frame 10 of suitable form on which an electric-motor 11 is mounted, the latter rotating a pinion 12 in mesh with a gear 13 on a shaft 14, the gear being capable of driving the shaft by reason of a

friction-clutch 15 equipped with an operating-sleeve 16 slideable on the shaft by means of a handle or lever 17 fulcrumed on the frame at 18. Obviously, any convenient form of clutch may be employed. Shaft 14 is revolvably supported in bearings 19, 19, and at one end it is fitted with a spur-gear 20 in mesh with a revolvably-supported smaller spur-gear 21 on a shaft 20^a driving a bevel-gear 21^a, which co-operates with a horizontal bevel-gear 22 on a shaft 23 rotatably mounted in an enlarged part or boss 24 of a skeleton-frame 25 supported from the main-frame by brackets 26, 27, (Figure 1). At its top end shaft 23 carries a flanged circular disc 28 over which the pasteboard, straw-board, or other fibrous cap or closure 100 is adapted to be invertedly fitted for the coating operation.

70 Shaft 23 by means of intermeshing spur-gears 29 and 30 drives another adjacent upright shaft 31 provided at its top end with a like flanged cap support. Six other of such shafts 33 are employed in two rows, as shown in Figure 2, each of the shafts having a spur-gear 34 in mesh with all of the adjacent gears, each shaft at its top carrying one of the cap supports 35 like the part 28. By this means all of these rotary members 28, 32, and 35, are simultaneously revolved at like speeds by the common driving means.

75 These eight revolving supporting members may be considered as divided into two groups of four each, each set having a spraying nozzle discharging streams of the coating liquid on to all four of the caps or closures held on the forms of each particular group, each nozzle being centrally disposed with respect to its set of revolving caps, all as is clearly illustrated in Figure 2.

80 These two nozzles each have liquid-discharging slightly downwardly-inclined passages 42, 43, one of each of such apertures playing its stream of coating liquid upon one of the fibrous caps or closures on one of the revolving supports.

85 The more or less viscous coating liquid is contained in a reservoir-tank 44 subjected to pressure, as by compressed-air entering the tank through a pipe 45 from a source not shown. A liquid discharge-pipe 46 which reaches nearly to the bottom of the interior of the tank delivers the coating liquid through a strainer 47 to a cross-pipe connection 48 by means of which the liquid is fed to two valves 49, 49, supported on brack-

ets 50 and 51 of the frame 25. The liquid passing through these valves flows upwardly through hand-valves 52, 53, and connecting pipes 54 to the two discharge nozzles 40 and 41.

The means for automatically stopping the rotation of the caps or closures undergoing treatment and for opening and closing the valves 49, 49, will now be described.

10 Shaft 14, between the bearings 19, 19, has a worm 60 driving a worm-wheel 61 on a suitably-supported shaft 62, one face of the worm-wheel having a cam-groove 63 cut therein. An arm 64 is rockingly mounted 15 on the main-frame at 65 and carries a roller 66 accommodated in the cam-groove, the arm 64 being connected by a link 67 with an arm 68 fastened to a jack-shaft 69 revoluble in bearings 70, 70, of frame 25.

20 The sliding stem 71 of each of the valves 49 is fitted with spaced collars 72, 72, between which is accommodated the bifurcated end portion 73 of an arm 74 fixed to the shaft 69, a spring 75 surrounding the 25 lower portion of the valve-stem and pressing upwardly against the lower collar 72. It will be understood, therefore, that by 30 rocking shaft 69 the two valves may be opened or closed conjointly or simultaneously.

A dog 80 is pivoted on the face of the worm-wheel 61 at 81 and is provided with a coil-spring 82 tending to swing it on its hinge mounting forwardly against a stoppin 35 carried by the worm-wheel, a rear stop-pin 84 projecting laterally from the face of the same wheel. Additionally, the appliance includes a hook-arm 85 hinged on the lever 17 at 86 and limited as to downward swinging by an abutment or stop-pin 40 87 carried by the pivoted hook 85 and fitting in an inclined slot or groove 88 of a stationary-strap 89 fastened to one of the bearings 19.

45 The operation of the appliance takes place practically as follows:

Assuming that each of the rotary supports 28, 32, and 35 is fitted with an inverted pasteboard, straw-board or other 50 fibrous flanged container cap or closure 100, the operator shifts or rocks the handle 17 to the left as the parts are viewed in Figure 1, thereby rendering the clutch 15 operative to connect the driving-gear 13 to the shaft 55 14. Immediately, the rotation of the motor-pinion 12 is transmitted through the gear 13 to the shaft 14 and through the various gears 21, 22, 29, 30, and 34, resulting in the simultaneous rotation of all of 60 the inverted cup-shaped members 100 and their supports. The cam-groove 63 is so shaped that upon the institution of the rotation of the parts specified, the two valves 49, 49, by reason of the rocking of shaft 69 65 through the connections 67, 68, will be

opened by the downward movement of their two stems 71 against the upward pressing action of their coil-springs 75. As soon as these valves open the coating liquid is forced from the tank 44, by reason of its being subjected to compressed air, through the pipe 46, strainer 47, pipe 48, valves 49, hand-valves 52 and 53, and pipes 54, to the two nozzles 40 and 41, each discharging four upper streams 101 from the four apertures 70 42 practically or nearly horizontally on to the flat tops of the caps or closures near their centers, and, owing to the rapid rotation of the caps, the streams of liquid will take a somewhat spiral path, as illustrated 75 in Figure 2, whereby the top surfaces of all eight caps will be adequately coated or covered with the solution. At the same time, these two nozzles discharge eight lower streams 101 from their apertures 43 80 against the sides or flanges of the caps or closures near their top edges, the liquid flowing down such sides and effecting a complete coating thereof, the surplus coating liquid from all of the streams being thrown off by centrifugal force and received in a rectangular pan 110 provided with eight flange-bordered apertures 111 in its bottom wall for the upward extension 85 therethrough of the various shafts carrying the flat rotary cap supports. From such receptacle 110 the surplus liquid is drained off through a pipe 112 and may be used a 90 second time.

After these nozzle streams have played 100 on the caps undergoing treatment for a suitable length of time, say 15 seconds, the valves are automatically closed by the action of the cam, but the caps and their supports continue their rotation for approximately 25 seconds longer to enable them to throw off the surplus coating liquid under the action of centrifugal force, thus giving the edges of the flanges a smooth 105 drip edge.

When the worm-wheel 61 has completed 110 one revolution, the dog or catch 80 engages the hook 85 and swings the arm 17 to the right, as the parts are viewed in Figure 1, rendering the clutch 15 inoperative, thereby 115 disconnecting the shaft 14 from the driving mechanism. As the hook 85 moves to the right, it is, at the same time, raised or lifted somewhat by reason of the engagement of its pin 87 with the inclined slot or 120 groove 88, and as the parts continue their rotation due to their momentum after the separation of the clutch elements, the dog 80 will snap free from the hook 85 just 125 previous to the parts coming to a standstill, so that to again initiate the rotation of the elements, it is merely necessary to shift or rock the handle 17 to the left, as described above.

As has been indicated, the upper streams 130

of coating liquid strike the flat or revolving surfaces of the caps or closures at or near their centers and then assume a somewhat spiral path owing to the compound action 5 of their velocity of issue from the discharge nozzles and the rotation of the caps, assuring a complete and adequate coating of the surfaces to which they are applied. It is to be observed that these upper streams of 10 coating material have only a slight vertical drop in passing from the nozzles to the revolving caps and are hence discharged upon the latter almost horizontally, and by reason of this construction the original velocity or speed of flow of the stream is not detrimentally cut down so as to hinder the adequate flow of the stream over the top surface of the cap.

The side streams which strike the cap 20 flanges near their top edges spatter back or upwardly sufficiently to provide a full and complete coating of these sides.

The coating liquid being somewhat viscous there is a tendency for the air in the 25 pasteboard or straw-board of the caps to be expelled therefrom by the solution entering the pores, such expelled air forming bubbles in the coating material, but these are quickly washed or flowed off by the stream of 30 fresh liquid so that the objectionable bubbles are easily gotten rid of.

It is to be noted furthermore that by employing a plurality of these caps near one another the excess liquid thrown from one 35 cap to another by centrifugal force is of advantage particularly on the flange or sides of the cap which assure complete and even coating thereof.

Although I have described and illustrated 40 in detail one embodiment of this invention, it is to be understood that the latter is susceptible of a variety of embodiments embodying the main and principal features of the invention. The exact and precise structural features shown and described are not 45 an essential part of the invention and these may be varied or modified within comparatively wide limits without departure from the substance and essence of the invention 50 and without the sacrifice of any of its material benefits and advantages.

I claim:

1. In a coating-appliance of the character 55 described, the combination of a horizontal disc adapted to support a flanged cap fitted

thereover, means to revolve said disc and cap, means to play a stream of coating liquid nearly horizontally on to the cap near but not at the center of the unobstructed top thereof and a downwardly inclined 60 stream slightly below the top edge of the depending flange of the cap, substantially as described.

2. In a coating-appliance of the character described, the combination of a horizontal 65 circular disc adapted to support a flanged cap fitted thereover, means to revolve said disc and cap, means to play a stream of coating liquid nearly horizontally on to the cap near but not at the center of the unob- 70 structed top thereof and a downwardly inclined stream slightly below the top edge of the depending flange of the cap, and auto- matically-acting means to stop the playing 75 of said streams permitting the cap to re- volve after such cessation to even the coating and throw off the surplus liquid by cen- trifugal force, substantially as described.

3. In a coating-appliance of the character 80 described, the combination of a horizontal disc adapted to support a flanged cap fitted thereover, means to revolve said disc and cap, and means to play a stream of coating liquid nearly horizontally on to the unob- 85 structed middle portion of the top surface of the cap near but not at the exact center thereof and during the rotation of the cap, substantially as described.

4. In an appliance of the character de- 90 scribed, the combination of a plurality of discs each adapted to have a flanged cap fitted thereover, means to revolve said discs, and means common to all of said discs to play streams of coating liquid simultaneously 95 on their caps during the rotation of the latter, substantially as described.

5. In an appliance of the character de- 100 scribed, the combination of a plurality of discs each adapted to have a flanged cap fitted thereover, means to revolve said discs, means 105 common to all of said discs to play streams of coating liquid simultaneously on to their caps during the rotation of the latter, and means controlling said streams of coating liquid to cause their cessation and to permit such discs and caps to revolve thereafter to even their coatings and discharge the sur- plus coating material from the caps by cen- trifugal force, substantially as described.

ESKEL NORDELL.
